HIGHWAY COMMUNICATIONS STANDARD

Dennis J. Foley and Richard A. Gilmore, Columbus, Ohio, assignors to Design Properties, Inc., Wellston, Ohio

Filed Aug. 16, 1972, Ser. No. 281,169

Term of patent 3½ years

Int. Cl. D29—02
U.S. Cl. D72—1 H

FIG. 1 is an elevational view of the highway communications standard showing our new design,

FIG. 2 is a side elevational view of the device shown in FIG. 1,

FIG. 3 is a rear elevational view,

FIG. 4 is a top plan view thereof, and

FIG. 5 is a bottom view thereof.

The post is broken away in FIGS. 1, 2 and 3 to indicate indeterminate length.

We claim:

The ornamental design for a highway communications standard, as shown and described.
